(57) **CLAIM**

The ornamental design for a sleeve for co-axial cable connector, as shown and described.

DESCRIPTION

FIG. 1 is a perspective view of a sleeve for co-axial cable connector showing my new design;
FIG. 2 is a side elevational view thereof, the other sides, top, plan and bottom plan views being mirror images;
FIG. 3 is a first end view thereof; and,
FIG. 4 is an opposite end view thereof.
The broken lines depict environmental structure and form no part of the claimed design.
